UNITED STATES PATENT OFFICE.

ROBERT R. WEAVER, OF CHICAGO, ILLINOIS, ASSIGNOR TO GENERAL AMERICAN TANK CAR CORPORATION, OF CHICAGO, ILLINOIS, A CORPORATION OF WEST VIRGINIA.

RAILWAY CAR.

Original application filed November 21, 1924, Serial No. 751,260. Divided and this application filed January 7, 1926. Serial No. 79,822.

My invention relates generally to improvements in railway tank cars, the present application being a division of my pending application for U. S. Letters Patent 5 Serial No. 751,260, filed November 21, 1924.

My primary objects are to provide in a car, and more particularly in a tank car having a box-like housing in which the tank is located, for the removal and replacement 10 of the roof portion by a simple and quickly performed operation and without risk of damaging the car, in which structures it is sometimes necessary to remove the tanks from the cars, as for example in the case 15 of repairs to be made, in which case the tanks are lifted out of the housings; to provide a novel and simple construction of car of the character stated; to provide for the proper thermal insulation of the car at the 20 joint between the roof section and the section thereof presenting the side and end walls; to provide for the so positioning of the refrigerating pipes in refrigerating cars of the type above referred to, that the tanks 25 may be removed from, and replaced in, the car housings through their upper ends, without obstruction from the pipes and without requiring the disturbing of the position of the latter, and other objects, as will be 30 manifest from the following description:

Referring to the accompanying drawings:—

Figure 1 is a plan view of a car of the type above referred to and embodying my 35 improvements. Figure 2 is a plan sectional view of the car, the section being taken immediately below the roof portion thereof at the irregular line 2—2 on Fig. 4 and viewed in the direction of the arrows, the 40 tanks being shown in plan. Figure 3 is an enlarged view in longitudinal sectional elevation of one end of the car, the section being taken at the line 3 on Fig. 2 and viewed in the direction of the arrow. Figure 45 4 is a section taken at the line 4 on Fig. 3 and viewed in the direction of the arrow. Figure 5 is an enlarged fragmentary sectional view taken at the line 5 on Fig. 1 and viewed in the direction of the arrow. Figure 50 6 is a broken section taken at the irregular line 6—6 on Fig. 5 and viewed in the direction of the arrows. Figure 7 is a plan view of the structure shown in Fig. 5, with the roof proper removed. Figure 8

is a broken, enlarged, fragmentary sectional view taken at the line 8 on Fig. 1 and viewed in the direction of the arrow; and Figure 9 is a face view of one of the plurality of similar lifting lugs provided on the roof portion of the car.

The particular construction shown involves an underframe illustrated more especially in Figs. 3 and 4 and of the fish-belly, center-sill type, the center sill being represented at 10 and extending longitudinally of the underframe from end to end thereof. This frame in addition to the center sill 10 comprises cross-bearers 11 arranged at different points along the center sill 10 and a body bolster 12 located toward opposite ends of the frame. The particular construction of center sill 10 shown which is of hollow form, comprises side walls 13 spaced apart and formed of plates 14 provided at their upper and lower edges with angle bars 15 and 16, respectively, rigidly secured thereto, and a plate 17 extending across the upper ends of the side walls 14 and resting upon the angle bars 15 to which they are secured as for example by rivets. The underframe shown is supported on wheel trucks, the wheels of which are represented at 18, the form of underframe shown being of well known construction. The structure also 75 comprises a platform, or floor portion, represented generally at 19 which is generally of well known construction, this floor portion being supported on the underframe and secured thereto in any desired manner, as for example in the manner well known in 80 the art.

The particular construction of car shown involves incorporation therein of two tanks provided more especially for receiving fluids which it is desired be maintained at a given 85 temperature regardless of atmospheric conditions, these tanks represented at 20 and which are of elongated form and circular in cross section being shown as located at opposite ends of the car and at the same distance from the center thereof.

The tanks 20 are shown as anchored in place on the platform of the car to hold them against displacement thereon, the anchorage means shown, and which form no 90 part of the present invention, being that disclosed in my above-referred-to application for patent, it being sufficient to say that 100

each tank 20 extends at its lower portion into a bed of suitable cushioning anchorage material located within a receptacle 21 firmly anchored to the underframe, with restraining straps 22 partially surrounding the tanks 20 and connected at their ends with the opposite sides of the receptacle 21.

Each tank 20 is provided at the upper portion of the end wall thereof nearest the center of the car with an inlet 23 connected together by a pipe 24 provided with a coupling 25 from which a pipe 26 leads to a point adjacent an opening 27 in the side of the car and through which connection with this pipe may be made for filling the tanks.

Each tank 20 is provided at its lower portion at the end thereof adjacent the center of the car, with a valve-controlled outlet 28, these outlets being connected together by a pipe 29 equipped with a coupling 30 for connection with a pipe for conveying the contents of the tanks to receptacles into which they are to be delivered, as for example to a storage tank (not shown).

The housing structure for the tanks 20 comprises end and side walls 31 and 32, respectively, and a roof portion 33, the wall portions 31 and 32 being built into each other and into the platform portion 19 of the car as is common in refrigerating cars, these wall portions being of plural-wall construction with spaces therebetween containing any suitable thermal insulating material. The side walls 32 at the center portion of the car contain the usual large door openings 34 equipped with doors 35 and above these door openings, with the smaller openings 27 which would be equipped with removable closures (not shown).

The side and end walls 31 and 32 are provided along their upper edges with side and end plates 36 which together form a rectangular frame 37 built into the spaced wall-forming portions of these walls. The roof portion 33 of the housing is likewise formed of a rectangular frame 38 of substantially the same size and shape as the frame 37 and comprising side plates 39 suitably connected together at their ends, the frame 38 resting upon the frame 37. The opposing surfaces of the frame 37 and 38 are internally grooved throughout their length at the sides and ends of the car, as represented at 40 and 41, respectively, these grooves containing thermal insulating material represented at 42 provided for the purpose of insulating the interior of the housing at the joint between these housing sections. The frame 38 is provided at intervals along its inner surfaces, at its sides and ends, with cleats 43, those at the sides of the car being located between adjacent carlines 44, as shown in Fig. 7, the cleats 43 which extend inwardly beyond the side plates 36 and 39 being rigidly secured to the frame 38 by bolts 45

extending through sides plates 39 and the cleats 43. The frame structure thus presented has secured to it the roof proper represented at 46 and the ceiling 47 spaced from the roof proper 46 to provide an air space 70 with thermal insulation located therein, the ceiling 47 being secured in place as by nailing it to the carlines 44. The roof portion 33 at its cleated portion is provided at intervals with vertically disposed bolts 48 having square upper ends 49 at which they extend into square openings 50 in the cleats 43, these bolts passing downwardly through the cleats 43, the ceiling 47, and through the horizontal flanges of the angle-clips 51, the nuts 52 of these bolts bearing against the undersides of the clips 51. Plates 53 resting on the upper surfaces of the cleats 43 and secured thereto by bolts 54 and extending across the upper ends of the bolts 48, prevent upward displacement of the latter in the application of the roof portion 33 to the side and end wall portions of the car. The angle clips 51 which are positioned at intervals in the angular spaces between the end and side walls 31 and 32 of the car and the roof portion 33 are connected with the side plates 36, the inner surfaces of which they overlap, by means of bolts 55 which extend through the side plates 36 and the depending flanges of the angle clips 51.

Provision is made for refrigerating the car, these means comprising refrigerating coils 56 for any suitable refrigerating medium, for example ammonia, arranged along the inner surfaces of the side walls 32. The coils 56 at each side of the car are connected together at their lower ends by pipes 57 extending below the platform 19 and provided with filling and drawoff valves 58 and at their upper ends, through couplings 59, by cross over pipes 60.

It will be understood from the foregoing that by removing the nuts 52 from the bolts 48, the roof portion of the car may be readily removed and replaced without dismantling any of the parts of the wall-forming portions of the car, to permit the tanks 20 to be bodily lifted, as by cranes, out of the car housing and replaced therein as desired, it being understood that the piping located directly above the tanks would be first removed. To provide for the ready attachment of the lifting device to the roof portion 33 as for example, the lifting element of a crane, the roof portion 33 is provided at intervals with upwardly extending apertured plates 61 secured thereto, as by bolts 62.

As an additional means for rendering the joint between the frames 37 and 38, in tight condition, I prefer to provide for the lapping of the outermost members 63 and 64 of the frames 37 and 38 at their opposing surfaces, as represented at 65, thereby forming

ing a lapped joint extending entirely around the housing structure; and the housing-forming sections are also so constructed and arranged that the ceiling portion 47 extends 5 below the upper edge of the plates 36, as shown in Fig. 5, forming a lapped joint at the inner surface of the housing.

While I have illustrated and described a particular construction embodying my improvements, I do not wish to be understood as intending to limit my invention thereto, as the same may be variously modified and altered without departing from the spirit of 10 my invention.

15 What I claim as new, and desire to secure by Letters Patent, is:

1. A car comprising an underframe and a housing-structure having a roof-portion, said housing-structure being formed of sections one of which comprises side and end 20 walls with a rectangular frame along the upper edges of the latter, the other of said sections comprising said roof-portion with a rectangular frame along its marginal edges seated on said first-referred-to frame, cleats 25 at the inner surfaces of said second-named frame, and means engaging said cleats and the section thereof comprising said side and end walls, for securing said sections together.

30 2. A car comprising an underframe and a housing-structure having a roof-portion, said housing-structure being formed of sections one of which comprises side and end walls with a rectangular frame along the upper edges of the latter, the other of said sections comprising said roof-portion with a rectangular frame along its marginal edges seated on said first-referred-to frame, cleats 35 at the inner surfaces of said second-named frame, angle-members connected with the one of said sections comprising said side and end walls and extending in registration with, and below, said cleats, and means engaging said cleats and said angle-members for securing 40 said sections together.

45 3. A car comprising an underframe and a housing-structure having a roof-portion, said housing structure being formed of sections one of which comprises said roof portion and is separate from the remainder 50 of the housing structure, said roof portion

section resting flatwise upon the upper edge portion of said other section, thermal insulating material interposed between the opposing surfaces of said sections, and means 55 releasably securing said roof portion in position.

4. A car comprising an underframe and a housing-structure having a roof portion, said housing structure being formed of sections one of which comprises said roof portion and is separate from the remainder of the housing structure, said roof portion section resting flatwise upon the upper edge portion of said other sections, the opposing 60 faces of said sections containing registering grooves extending along the sides and ends of the car, thermal insulating material located in said grooves, and means releasably holding said roof portion section in 65 position.

5. A car comprising an underframe and a housing-structure having a roof portion, said housing structure being formed of sections one of which comprises said roof portion and is separate from the remainder of the housing structure, said roof portion section resting flatwise upon the upper edge portion of said other sections, the opposing 70 faces of said sections containing registering grooves extending along the sides and ends of the car, thermal insulating material located in said grooves, said sections having lapped portions outwardly beyond said 75 grooves forming a lapped joint beyond said insulating material, and means releasably securing said roof portion section in position.

6. In a tank-car, the combination of an underframe, a housing-structure, a tank in 80 said housing-structure, and cooling pipes located in said housing-structure along side-walls thereof, whereby said pipes do not obstruct lifting of the tank from its position in said housing, the upper portion 85 of said housing-structure being formed as a section separate from its lower portion and removable therefrom without damaging the housing structure, for the purpose set forth.

ROBERT R. WEAVER.
